(57) **CLAIM**

We claim the ornamental design for a pointer tool, as shown and described.

DESCRIPTION

FIG. 1 is a front perspective view of a pointer tool, showing our new design;

FIG. 2 is a front elevation view thereof;

FIG. 3 is a rear elevation view thereof;

FIG. 4 is an enlarged top plan view thereof, in order to show aspects of the design not otherwise apparent;

FIG. 5 is an enlarged bottom plan view thereof, in order to show aspects of the design not otherwise apparent;

FIG. 6 is a left side elevation view thereof;

FIG. 7 is a right side elevation view thereof; and,

FIG. 8 is a front perspective view thereof, shown with environment.

The broken lines are directed to environment and form no part of the claimed design.

The wire frame lines shown throughout the views are intended to indicate surface contour.
